ASSIGNORS TO STRACHAN & HENSHAW, LIMITED, OF WHITEHALL, BRISTOL, ENGLAND

PAPER-BAG-MAKING MACHINE OR THE LIKE

Application filed June 1, 1927, Serial No. 195,813, and in Great Britain June 8, 1926.

This invention relates to machines for making paper bags, packets or the like of the type wherein a transverse portion of a surface element is folded up in itself and adhesively secured, or to mechanisms associated with machines of this class.

For the sake of convenience and clarity, the invention will hereinafter be described in association with a machine of known kind for making paper bags wherein paper in a continuous web is drawn from a roll, folded longitudinally on formers and pasted to form a continuous tube which is severed into appropriate lengths for bag lengths, and the bag blanks are then folded transversely at their end margins which are pasted or adhesively secured to the body of the blanks to form the closed bottoms of the bags.

In the art concerned with making paper bags and the like from a continuous web or tube which is severed into lengths, folded transversely and the folded portion secured by adhesive, considerable difficulty has been experienced in effecting the folding and pasting operations without trouble arising, particularly at high speeds.

In connection with known bag-making machines of the above kind, various proposals have been made for providing means adapted temporarily to grip the fold of the bag within the slot to prevent displacement of the bags. For example it has been proposed to fold the end of a bag into a slot-like part upon the folding roll, formed by or between a fixed edge thereof and a gripper blade which constitutes one side of the slot formation and which is adapted to move across the slot to grip the folded part.

The object of the present invention is to obviate difficulties which have been found to occur in connection with known machines or mechanisms, particularly when such are operated at high speeds, and to provide means whereby the folding and pasting operation may be carried out in a positive and effective manner and so that the recurring sequence of folding, gripping and pasting the bags may be carried out at unusually high speeds with mechanical accuracy and reliability.

In machines where the bag is folded against a gripper blade uniform and even folds of the bags are difficult or impossible to attain and in contradistinction to arrangements of this kind, according to the present invention the bag is folded independently of any gripping device between the fixed edges of a slot formed in or upon the folding roller, while the gripping blade is adapted subsequently to come into operation to engage the formed fold. The folded part may be gripped or engaged by a gripper device or means operating inward or below the edges of the slot. For example, the folding means may comprise a rotary dipper blade or device adapted to press or fold the end margin of the bags into a narrow slot formed between fixed edges in or carried by the folding roll, in combination with a rotary resilient gripping blade or device adapted to engage the folded part and grip it against the forward edge of the slot (having regard to the direction of rotation), the following or back portion or part forming the rear of the slot being adapted to mask the operations of the gripping blade.

The pasting means comprises a paste-applying member, bar or the like adapted to take or receive a supply of paste from a paste-carrying roll or member, characterized by the feature that said bar receives its supply by removing or wiping off paste from the roll or member in a series of contiguous lines or zones, as by making the movement of the paste-carrying surface appropriately slow in relation to the operations of the paste-applying member.

It is preferred that the pasting device is in the form of a blade or bar having a paste-bearing portion which is grooved, countersunk or rabbeted in order that it may carry with it from the paste roll and retain a compact elongated charge or thin line of paste rather than a mere surface layer thereof.

According to the invention the paste box adapted to supply the paste roll with a layer of paste is preferably pivotally or displaceably mounted so that the paste roll may be moved into a position in which it is out of reach of the pasting blade. The paste roll intersects or enters a portion of the paste

box and the layer of paste carried away by the paste roll may be governed or controlled by an adjustable slide or gate.

In the accompanying drawings:—

Figure 1 is a side elevation partly in section of folding, pasting mechanism and associated parts, constructed according to one form of the invention.

Figure 2 is a section taken on the line A—B of Figure 1.

Figures 3 and 4 are diagrammatic representations of the pasting and folding operations, Figure 3 also showing an alternative form of folding and gripping device for the bags.

Figure 5 is a diagrammatic sectional side elevation of pasting and folding mechanism and a modified form of drive for a paste-carrying roller.

In carrying the invention into effect according to one convenient mode, as applied by way of example to paper-bag-making machines, the end of the machine from which the bag blanks are delivered is provided with a cylinder 1 of metal or other suitable material rotatably mounted on bearings upon a shaft 2 carried in the side frames of the machine. This cylinder is referred to herein-after as the folding roll. This roll may be suitably driven through a gear 22 and is usually adapted to make one revolution for each bag received, rotation being capable of being effected at high speed.

The surface of the roll is provided with a narrow slot 1a transverse to the travel of the bag and parallel to the axis of the roll in which the end margins of the bags are adapted to be folded. This slot communicates inwardly with a transverse recess or cavity 1b or with the interior of the cylinder (in the case in which it is made hollow, see Figures 3 and 5) adapted to accommodate a gripping device according to the invention.

The gripping device comprises preferably a thin flexible steel blade 3 mounted upon a transverse bar or shaft 3a in a plane displaced from the axis of the shaft or the blade may be carried by an element extending from a rock shaft or carried upon arms 3b or a frame mounted upon the rock shaft or pivots 3a (see Figures 3 and 5). The preferred position of the pivot 3a or pivoted axis of the shaft 3a is considerably eccentric or displaced with respect to that of the roll and disposed slightly forward of the folding slot 1a taking the direction of rotation of the roll into consideration. In determining the position of the pivot the factor should be taken into consideration that the folded portion of the bag should be gripped between substantially parallel surfaces and that in the present case the resiliency of the grip is attained by the use of a flexible member. A mounting for the folding blade as above described should be such

that the edge of the blade 3 in its movements describes an arc which intersects the circumference of the roll adjacent the folding slot and the movement is such that, and accommodation is provided so that, the gripper normally or in its inoperative position lies below or under cover of the part forming the rear of the slot.

The gripper blade 3 may be given the requisite oscillatory movement by any suitable means so that it functions in synchronism with a dipper device for folding the bag margin into the folding slot. For example, the rocking shaft 3a may have fixed thereto an arm or lever 3c located at one end of the cylinder. This arm or lever or the arm 3b (Figures 3 and 5) carries a roller 3d adapted to engage a cam 4 fixed coaxially with the shaft 2 or a trunnion of the folding roll. The cam roller may be maintained in contact with its cam by any suitable form of spring means, such as 5. The cam 4 is preferably made so that its angular position may be adjusted in order to alter the timing of the device as desired. Interchangeable cams may be provided to afford a means of varying the timing or operation of the gripper 3.

It will be observed that as the roll revolves about its shaft the cam 4 will cause the rock shaft 3a to oscillate the gripper blade 3 and cause it to engage the forward side of the slot 1a and hold the folded bag for a predetermined period corresponding with an arc of the revolution of the folding roll.

The folding slot 1a may be formed integral with the cylinder constituting the folding roll as by casting, see for example Figures 3 and 5, or the cavity accommodating the gripper blade (Figure 1) may be provided at its outer portion with a pair of plate members 1b, 1c which may be adjustably secured to provide a folding slot of variable width. The forward edge of the folding slot or plate 1b is preferably located in a radial plane of the roll and is of a depth or thickness such as to afford a suitable bed or gripping surface against which the gripper blade may operate to engage and hold the folded margin of the bag while the rear or following side of the slot is cut away or provided with a clearance to allow for the arcuate or oscillatory movement of the gripper blade and to provide accommodation for the gripper below the rear part of the slot. Where a separate plate, such as 1c, is employed in connection with the formation of the slot, the under side of this plate may be chamfered or made concave for the purpose of providing the necessary clearance. The width of the slot may be varied by adjustably mounting the plates 1b, 1c.

The bag is folded into the folding slot by the action of a rotating dipper device which may be conveniently provided in the form of a flexible blade member 6 (Fig. 1) or in-

tegral rib 7 (Figures 3 and 5) carried by a rotatable upper roll or support and it will be understood that the dipper in conjunction with the fixed edges of the slot performs the folding operation of the gripper device. The roller or support for the dipper may be a mutilated roller comprising two end pieces or drum heads 8 having an intermediate disc-like part 8a of slightly larger diameter than the parts 8. The purpose of the part 8a is to hold down or prevent the middle part of the bags from rising. This blade 6 or rib 7 is adapted to synchronize with the folding slot 1a so that it meshes therewith and folds the bag margin into the slot slightly in advance of the operation of the gripper member 3, which subsequently functions to engage and grip the preformed fold.

While the dipper may be formed integral with its roller or support, it is preferred to provide it in the form of a thin flexible blade, as shown in Figure 1, detachably or adjustably fitted to the upper roller. For example, the blade 6 may be adjustably secured by the aid of slots 6a to a bar 6b mounted within a longitudinal cavity 9 in the dipper roller or support and secured to the heads 8 at 8b, the disc 8a being also formed with a cavity 8c to accommodate the dipper 30 and a pasting device to be presently described.

For the purpose of applying paste or adhesive to the bag in the appropriate situation before or as folding is taking place, the dipper roller or support carries or accommodates a radially arranged longitudinal pasting bar 10 disposed adjacent the dipper member and preferably adjustable radially and in relation thereto as will hereinafter appear.

The pasting bar 10 is adapted to be reciprocated radially so that the path 10a (Figure 1) described by its outer extremity is eccentric to that of the roll in association with which it is carried. At a suitable point in its eccentric path the bar 10 is adapted to gather a charge of paste from a paste roll 11. This may be accomplished in any suitable manner for example the dipper bar may be carried by or connected to a pair of eccentric sheave members 12 disposed with recesses 12a formed in the heads 8 and mounted upon fixed eccentrics 13 so that as the roll revolves the pasting end of the bar as it approaches the (see Figure 1) the folding slot protrudes only sufficiently to deposit its charge of paste upon the bag (see position shown in Figure 3) and then recedes inwardly of the dipper blade during the folding operation. When, however, the folding operation has been completed, the dipper and the pasting bar are rotated into a position in which the pasting bar is intended to gather a fresh supply of paste from the paste roll 11 (see Figure 4). In this position the pasting bar, owing to the eccentric mounting, is protruded above the

level of the dipper blade so that while the pasting bar takes a supply of paste the dipper blade or bar passes clear.

The paste supply device comprises a roll 11 (or other continuously slow moving surface) upon which a layer of paste is spread, so geared or driven that it revolves at a slow rate of speed relatively to the rate of revolution of the dipper blade and pasting bar. The rate of relative revolution is adjusted so that at each revolution the pasting bar removes or wipes off from the paste layer 11a (Figures 3, 4 and 5) a narrow zone or line of paste longitudinally across the width of the roll, and at each succeeding revolution contiguous lines or zones of paste are successively removed, as exemplified at 11b (Figure 3), thus ensuring that the paste is cleared from the roll as it revolves and a substantially clean (roll) surface is returned to the paste box or other source of supply. By this means it will be observed that a high rate of pasting operation can be attained while cleanliness is preserved, eliminating any tendency for paste to be thrown by the paste-carrying roll 11 by centrifugal force.

To facilitate the removal of the paste from the paste roll in the manner above described, and with a view to delivering a constant predetermined and appropriately disposed quantity of paste to each bag in turn, the outer extremity of the paste bar 10 may be rabbeted as at 10c (see Figure 5) on its forward side or otherwise formed in such a manner that a paste-receiving or retaining recess is afforded.

The paste-carrying roll 11 may be supplied from a paste box 14 of known general kind and the quantity of paste carried away upon the roll may be varied by means of a sliding gate 14a, the position of which relative to the periphery of the roll is adjustable by the aid of a screw 14b or other device. The paste box is preferably mounted upon the extensions of the paste roll spindle 11b and for this purpose is provided with a pair of sleeve members which are carried in cradles 15 which have open slots to facilitate the removal of the box and roll. The cradles 15 are pivotally mounted upon caps 15a associated with the shaft 24 and carry a rotatable shaft 24c upon an extension thereof. This shaft 24c has a pair of eccentrics 16 keyed thereto. Each eccentric is provided with a sheave link member 16a pivoted to the side frames of the machine or other fixture. The shaft 24c has a handle 17 whereby it and the eccentrics may be rotated so that the paste box and roll may be caused to oscillate about the cradle pivots. A set screw 17a affords a convenient means for locking the paste box and roll in an adjusted position. This oscillatory movement enables the paste roll to be moved or raised to a position in which its periphery is out of reach of the

pasting bar 10 as it passes, thus affording a convenient means for quickly putting the pasting operation out of action as may be desired.

- 5 Any suitable means may be provided for driving the paste-carrying roll at a very slow speed, a suitable reduction drive being illustrated in Figure 2. The pinion 25 mounted on the shaft 24 is adapted to mesh with a 10 gear 26 loosely mounted upon a sleeve 27 carried by a stub shaft 28 arranged in the extension of the shaft 11b of the paste roll. To facilitate removal, the stub shaft of the paste-carrying roll shaft may be detachably 15 engaged one with the other by the aid of a tongue and groove or like joint. The gear 26 is provided with a housing or casing member 26a for a planet pinion 29 and an oppositely disposed counterpoise weight 29a, the 20 housing being rotatably mounted upon a sleeve member 27a. Both the sleeve members 27, 27a are provided with external pinions 30, 30a but whereas the sleeve member 27 is held stationary by the pin 31 the sleeve 25 27a is adapted freely to rotate upon the stub shaft. The pinion 30 causes the planet pinion 29 to rotate about its axis as it is revolved about the pinion 30 by the gear 26, and to drive the sleeve 27a through its pinion 30a. 30 This drive is communicated to the stub shaft preferably through a spring clutch 32 which is anchored to the sleeve 27a and mounted around a collar 28a on the stub shaft, the arrangement being such that normally the 35 drive through the clutch causes the spring to bind tightly on the collar and so communicate motion to the stub shaft.

In order to set the position of the paste-carrying roll, or in order to bring a fresh 40 supply of paste into use, the stub shaft may be provided with an extension upon which a hand wheel 32a may be mounted. By rotating this hand wheel in the same direction as that in which it is adapted to be driven, 45 the collar is freed from the clutch by reason of the springs unwinding slightly. Similarly by rotating the hand wheel faster than the rotation imparted to the shaft by the driving gear the operator is able to manipulate the 50 paste roll by hand when the machine is in motion.

In order to press the part of the bag folded by the cooperative action of the dipper, folding slot and the gripping blade, a roller 18 is 55 mounted adjacent the roller 1 so that it operates in rolling contact therewith. This roller is preferably driven at a surface speed corresponding with that of the folding roll 1. The roller 18 is adapted to press the folded 60 marginal part of the bag into contact with the body of the bag but in order that the pressure shall not be applied directly to the pasting line, means are provided such as a transverse cavity or slot 18a. This slot is adapted 65 to register or synchronize, during the rota-

tion of the roller, with the paste line so that while pressure is brought to bear on the bag at either side of the paste line, the paste itself is not actually subjected to the pressing action and, consequently, is preserved from being squeezed out either laterally or on to the body of the bag.

In conjunction with the pressing roller 18 and in order to ensure that the bags leave the folding roller when released by the gripper blade, a series of stripping wires or fingers 19 are provided which extend between the pasting roller and the folding roller (see Figures 1 and 5). The wires 19 are located below the periphery or surface of the folding roller and in order to accommodate them the roller 1 is provided with circumferential slots 1d and the gripping blade 3 is formed with corresponding slots 3e in register with the circumferential slots 1d. The stripping wires 19 are led or given a configuration such that the bag is deflected from the folding roller shortly after its leading end has passed by the pressure roller 18. From the stripping wires the bags pass in succession to some suitable form of conveyor device such as a moving felt or cotton belt, tapes or the like, to a drying or pressing device from which they are delivered by any suitable mechanism.

The folding and pasting mechanisms above described may be driven and given their appropriate rotations and movements by any suitable means. For example, a gear wheel 20 mounted on the shaft of the roll 8, may receive power transmitted from the bag machine so that the pasting roll revolves at a suitable rate. The pasting roll has a gear 21 locked to it laterally by bolts or other means and meshes with a gear 22 similarly locked to the side of the folding roll 1, so that the pasting roll and folding roller rotate in unison. The gear 21 also meshes with a gear wheel 23 loose upon the transverse shaft 24 to which it is preferably connected by clutch means. For example, a disc 24a may be rigidly mounted upon the shaft 24 and the gear 23 may be locked to the disc 24a by a nut 24b. The purpose of this clutch arrangement is to enable the setting of the gear wheel 23 with respect to the disc 24a and shaft 24 to be varied or angularly adjusted.

According to a modification the relatively slow drive for the paste-carrying roller from the paste-applying roller may be communicated by a device such as shown in Figure 5 in which an eccentric sheave 33 mounted on an eccentric carried by the shaft 40 of the pasting roller, is connected by an arm 34 to a link 34a pivoted coaxially with the paste-applying roller 11. This link 34a carries a pawl 35 which is adapted to engage with a ratchet wheel 36 so that as the link is oscillated the pawl 35 drives the paste-applying roller 11 through the ratchet wheel and at an appropriately slow speed.

Having now described our invention, what we claim as new and desire to secure by Letters Patent is:—

1. Means for folding paper bags or the like having a dipper blade adapted in co-operation with a folding roller to fold a transverse portion of a bag blank upon itself and wherein the dipper blade is adapted to co-operate with a slot having fixed bag blank engaging edges carried by the folding roller so that the blank is folded between the two edges of the slot, gripping means carried by the folding roller and operative means adapted to actuate the gripping means to engage the folded part subsequently to the formation of the fold.

2. Means for folding paper bags or the like having a dipper blade adapted in co-operation with a folding roller to fold a transverse portion of a bag blank upon itself and comprising a folding roller provided with a transverse slot having bag engaging edges, a dipper blade adapted to enter the slot to fold the bag blank between the edges thereof, and a resilient gripper blade carried by the folding roller and operative means adapted to actuate the gripper blade to engage the folded part subsequently to the formation of the fold to grip it against the forward edge of the slot.

3. Means for folding bags or the like having a dipper blade adapted in co-operation with a folding roller to fold a transverse portion of a bag blank upon itself and comprising a folding roller having a transverse slot and a gripper blade pivoted within the folding roller and positioned so that in its normal position its outer end lies inward of the rear edge of the slot while the blank is being folded into the slot and operative means to pivot the gripper blade to cause it to engage the folded part subsequently to the formation of the fold to grip the fold against the forward side of the slot.

4. Means for folding bags or the like having a dipper blade adapted in co-operation with a folding roller to fold a transverse portion of a bag blank upon itself and comprising a resilient gripping blade pivotally mounted within the folding roller the axis of movement of said blade being in advance of the forward side of the slot so that in operation the outer edge of the gripping blade has an arcuate path which intersects the circumference of the folding roller at a point coinciding with the forward folding edge of the slot.

5. Means as claimed in claim 3 wherein the rear edge of the slot is undercut to accommodate the outer edge of the gripping blade in its normal position.

6. Means as claimed in claim 4 wherein one edge of the slot is chamfered to correspond with the arcuate path of the gripper blade.

7. Means for folding bags or the like hav-

ing a dipper blade adapted in co-operation with a folding roller to fold a transverse portion of a bag blank upon itself, a pasting means for pasting the folded part and comprising a pressure roller in rolling contact with the folding roller and adapted to press the folded part of the bag, said pressure roller having a transverse slot to accommodate the pasted portion, rotation being given to the roller to cause the slotted part to synchronize with the pasted part or line.

8. Means as claimed in claim 2 wherein the transverse slot is formed by a pair of plates detachably secured to the folding roller.

9. Means as claimed in claim 2 wherein the transverse slot is formed by a pair of plates one of which is adjustably mounted upon the folding roller.

10. Means for folding bags or the like having a dipper blade adapted in cooperation with a folding roller to fold a transverse portion of a bag blank upon itself and a pasting means for pasting the folded part, said pasting means comprising a paste carrying member, a rotary paste bar, means for rotating said bar to cause it to take a supply of paste from the member and transfer it to the bag blank, and means for advancing the paste carrying member to expose a fresh supply to the paste bar, the relative speeds of the paste bar and the paste carrying member being such that the paste bar removes the paste from the paste carrying member in a series of contiguous zones.

11. Means for folding bags or the like having a dipper blade adapted in cooperation with a folding roller to fold a transverse portion of a bag blank upon itself and a pasting means for pasting the folded part, said pasting means comprising a paste container, a paste carrying roller receiving paste from said container, means for rotating said roller at a low surface speed, a rotary paste applying bar operatively associated with said roller means for rotating said bar, to cause it to remove a supply of paste from said roller and transfer it to said bag blank, the relative speeds of the roller and bar being such that the paste is removed from the roller in progressive zones so that a substantially clean surface of the roller is returned to the source of supply.

12. Means as claimed in claim 11 wherein the paste applying bar is formed with a rabbeted edge whereby it removes a constant predetermined quantity of paste at each operation.

13. Means as claimed in claim 10 wherein the paste carrying member is mounted in displaceable bearings and means are provided for displacing such bearings to move the paste carrying member out of the path of the paste applying bar.

14. Means for folding bags or the like having in combination a dipper blade carried by
